CLAIM

The ornamental design for a vertical file, as shown and described.

DESCRIPTION

FIG. 1 is a right side elevational view of a vertical file showing my new design, the left side elevational view being a mirror image thereof;

FIG. 2 is a front elevational view, the rear elevational view being a mirror image thereof;

FIG. 3 is a top plan view thereof;

FIG. 4 is a bottom plan view thereof; and

FIG. 5 is a top, right front perspective view thereof.

FIG 1

FIG 2

FIG 3

FIG 4

FIG 5
